UNITED STATES PATENT OFFICE.

PAUL J. LAPHAM, OF GENOA, ILLINOIS, ASSIGNOR TO LACENE MANUFACTURING COMPANY, OF MANCHESTER, NEW HAMPSHIRE, A CORPORATION OF MAINE.

LEATHER-MARKING MACHINE.

1,103,520.

Specification of Letters Patent. Patented July 14, 1914.

Original application filed October 27, 1906, Serial No. 340,889. Divided and this application filed June 12, 1912. Serial No. 703,204.

To all whom it may concern:

Be it known that I, PAUL J. LAPHAM, a citizen of the United States, and resident of Genoa, in the county of Dekalb and State of Illinois, have invented an Improvement in Leather-Marking Machines, of which the following description, in connection with the accompanying drawings, is a specification, like letters on the drawings representing like parts.

My invention is a machine for grading leather by skiving and marking the leather piece, and this particular case relates more particularly to the marking mechanism, being a division (by requirement of the Patent Office) of my original application Serial No. 340,889, filed October 27, 1906. The machine is primarily intended for use in grading relatively stiff leather pieces such as are used for shoe-soles, taps, counters, etc.

The machine and its advantages will be explained and the operation thereof set forth in connection with the accompanying drawings, which present a preferred construction of my invention.

In the drawings, Figure 1 is a central vertical longitudinal sectional view, parts being shown in side elevation for clearness of illustration; Fig. 2 is a central vertical section 30 of a portion of the marking mechanism; Fig. 3 is a horizontal section thereof taken on the line 3—3, Fig. 2; Fig. 4 is a transverse vertical section taken on the line 4—4, Fig. 1; Fig. 5 is a similar sectional view taken on the line 5—5, Fig. 1; Fig. 6 shows the marking wheel in side elevation; Fig. 7 shows in side elevation the controlling cam in accordance with which the grading mechanism is set; Fig. 8 is a fragmentary sectional view on the line 8, Fig. 1; and Fig. 9 is a view in side elevation showing the driving mechanism.

My invention relates to that class of machines in which the leather piece to be graded is entered between receiving members at the front of the machine which operate to position setting mechanism for transmitting the determinations or measurements of the leather which has been felt of by the receiving members, and skiving mechanism which then evens the leather by trimming off the uneven places in accordance with the determinations of said previously mentioned mechanisms, the leather being

marked by marking mechanism to correspond to the thickness determined. 55

One feature of my invention resides in having the marking take place after the skiving or trimming as distinguished from previously thereto, which has heretofore been the rule. By this means I secure 60 clearer and better marking inasmuch as the marking die makes its impressions on absolutely even stock instead of on uneven stock.

Another feature of my invention resides 65 in having the marking die stationary, thereby practically eliminating a chief source of unreliability in those marking mechanisms in which the marking wheel or die has been required to move up and down and go 70 through various other automatic adjustments during movement. Also I provide means, preferably controlled by the leather itself whereby the marking takes place invariably at a predetermined distance from 75 one end of the leather piece, and the marking is done by a hammer-like movement of the leather against the relatively stationary marker.

While my invention may be carried out in 80 a wide range of mechanical forms, the form preferred for purposes of illustration to make the invention clearly understood is that shown in the drawings.

A rotary marker 1, provided with projecting dies 2 and fast on a shaft 3, is journaled in brackets 4 projecting rearwardly from the rear uprights 5 of the main frame of the machine, and immediately adjacent and at the rear of said marker is a pair of 85 rolls 6, 7, also carried by said brackets, the latter being journaled in journal blocks 8 mounted to slide toward and from the roll 6, which has simply rotary movement in the brackets. The shaft 9 which carries the roll 90 7 projects at its opposite ends beyond the slide blocks 8 and is connected by links 10 to the projecting ends of a rod 11 which passes through a lever 12 whose front end 13 is in position to engage the bottom end 100 of a hammer or striker 14 having guided vertical movement in the brackets 4 directly beneath the marker 1. The lever 12 is steadied and controlled in its movement by a pair of rolls 15 carried on a cross bar 16. 105 at the rear end of said lever and mounted in a recess 17 which is formed to extend obliquely upward and forward in a block 18

secured to a cross plate 19 of the brackets 4, as best shown in Figs. 2 and 3. The slot 17 is open at its outer end 20 to allow the necessary play or movement of the lever 12. Thus when the stock is fed along beneath the die 1 and enters between the rolls 6, 7, it thereby instantly separates said rolls and, as the lower roll is herein shown as relatively fixed, said separating movement causes the upper roll 7 suddenly to rise, thereby, through its links 10 and connecting mechanism, operating the lifting lever 12 to forcibly raise the striker 14 against the underside of the leather, thereby driving said leather up with a considerable impact against the opposite die 2 of the die wheel 1. The forward end of the leather piece being marked is held by the rolls 6, 7, while the intermediate portion of said leather piece rests upon a skiving knife 21, and the rear end or following end of the leather piece is firmly held by the adjacent rolls 22, 23 of the skiving or evening mechanism. This gives a firmness and certainty of position to the leather piece so that it is positively gripped firmly at its opposite ends while receiving the marking impact, and inasmuch as said impact takes place instantly as soon as the forward end of the leather piece arrives between the rolls 6, 7, it results that the mark is applied to each leather piece at the same predetermined distance from the forward end thereof as the successive pieces arrive in marking position. A further object is to give the leather an instantaneous blow-like mark, and while this object can be secured by various mechanisms, I have provided the striker or hammer 14 which is thrown or moved suddenly and forcibly against the under side of the leather while the latter is moving forward beneath the marker 1, and this blow is sufficiently sudden to prevent blurring notwithstanding that the marker is stationary. As shown, the space between the hammer 14 and the die 1 is considerably greater than the separation of the rolls 6 and 7 when the latter is raised by the entrance of the sole, so that when said entrance suddenly raises the roll 7 and hence, through the members 10 and 12, tends to throw upward the hammer 14, the said hammer, having struck the leather, drops back slightly. In this preferred embodiment of my invention, I positively drive these various rolls so as still further to provide accuracy of movement and position of the work, a gear 24 being herein shown as secured on the shaft of the roll 6 and driven by the drive gear 25 of the roll 23 in mesh with a gear 26 on a shaft 27 driven by a pinion 28 on the drive shaft 29 (which may be driven by belt and pulley at one end, not shown.) The roll 22 is driven by a large gear 30 and pinion 31, the latter on the main drive shaft 29. To insure the turning of the die wheel 1

into proper position so as to mark the leather piece with that number or character which corresponds to the thickness to which it has been skived or evened by the trimming knife 21, I provide automatic thickness-measuring mechanism at the front of the machine and from which motion is communicated to the die wheel by a gear 32 fast on the shaft 3 of said die wheel and actuated by a gear 33 fast on a shaft 34 which carries one or more limiting cams 35, said shaft being vertically adjustable in the rear uprights 5 of the frame before mentioned. As herein shown, there are two of these limiting cams adjacent respectively to the opposite ends of the shaft 34, and at about the middle of said shaft is a toothed member or gear 36 in mesh with a segmental rack 37 extending vertically at the rear end of a transmission lever 38 pivoted on a rod 39 on the front uprights 40 of the main frame of the machine. At its forward end beyond said pivot rod 39, the lever 38 has a vertical toothed segment or rack 41 meshing with an upstanding rack 42 supported in a frame 43 mounted for vertical movement in said uprights 40. A spring 44 yieldingly supports this rack 42 in said frame, and the latter is given desired downward pressure by end springs 45 adjustably mounted in the end uprights 40. Below this mechanism work-receiving members, herein shown as rollers 46, 47 are mounted in the frame, the latter being vertically movable and pivotally connected at its opposite ends on trunnions 48 in a frame 49. A track member or frame 50 is mounted to move with the roller 47, and traveling in a groove or track 51 thereon is a sliding carriage 52 guided by the inturned edges 53 of the frame 43 and provided with a roller or wheel 54 at its lower end to travel in said track 51 and with anti-friction rolls 55 on its upper side bearing on a cross beam 56 of said frame 43. Thus when an uneven piece of leather enters between the work-receiving members and thereby lifts the roll 47 more at one end than at the other, the carriage 52 will instantly slide to the lower end so as to gage or measure the thinner edge or portion of the leather piece at that moment, the result being that the frame 43 and hence the connecting rack and pinion mechanism 42, 41, 38, 37 and 36 are correspondingly operated so as automatically to adjust the limiting cams 35 in accordance with said thin spot thus determined. Guide wheels 57 are preferably provided in the uprights 40 for directing the frame 43 in its vertical movements, and buffers 58 are provided for stopping the sliding member in its endwise movements.

From the foregoing description, it will be understood that the measuring impulses of the work-receiving members are transmitted by the train of mechanism last described

and by the gears 33, 32 to the die wheel 1. In order to lock said die wheel in the desired position, I provide locking devices of any suitable form, herein shown as threaded bolts 59 adjustably mounted by nuts 60 in the end frames 61 of the upper roll 23 of the skiving mechanism, said bolts having V-shaped upper ends 62 to enter correspondingly shaped notches 63 formed in the eccentric periphery of the cams 35 (Fig. 7). As the leather piece is felt of or has its thickness determined by the work-receiving members 46, 47, it passes along a guideway 64 and beneath a hold-down 65 which serve to direct it accurately between the regulating rolls 22 and 23 of the skiving mechanism. Thus, as soon as the leather piece has had its thickness measured or ascertained by the feeler mechanism at the front of the machine, said thickness measurement being transmitted by the intervening transmitting mechanism back to the limiting cams 35, the leather piece is fed forward by the receiving rolls 46, 47 and its front end engages between the rolls 22, 23, thereby lifting the latter and instantly engaging the locking bolts 59 with said cams, thereby locking the latter against further movement and holding them in their automatic adjustment, in which locked position it holds the marker of the marking mechanism until the leather piece has been skived and correctly marked. To permit further adjustment and to enable the operator to regulate the height of the shaft 34 and cams 35 with such nicety as may be desired with relation to the skiving knife 21, I provide a wedge block or bar 66 operated by a threaded screw 67 and hand wheel 68, as best shown in Fig. 4, and journal the cam shaft 34 in a vertically movable carrier or frame 69 mounted to slide up and down in the uprights 5 and provided with inclined upper ends 70 for engaging the wedge blocks or bar 66. This carrier or frame 69 is normally held upward by springs 71. The receiving roll 46 is driven by a gear 72 in mesh with the pinion 31, and the roll 47 is driven by a gear 73 in mesh with the pinion 26.

50 The operation: As the operation of the feeler mechanism or thickness-determining portion of the apparatus and the transmitting mechanism, the evening or skiving mechanism, and the mechanism as a whole for grading the leather pieces (using the word "grading" generically to cover the mechanism which acts upon the leather piece, whether for evening or marking) are not claimed herein but in the parent case, 55 where the full operation is explicitly set forth, it is unnecessary to recapitulate the details of operation herein, this case relating primarily to the marking mechanism *per se*. As the stock passes between the receiving rolls, it raises the upper one, tilting

the same if the stock is sufficiently uneven to do so, and thereby the superimposed vertically movable mechanism and rack and pinion connections from the front to the back, transmitting the measurement thus ascertained to the notched limiting cams 35 and their shaft 34, whose gear 33 is correspondingly turned by the rocking of said shaft and thereby instantly, through the gear 32, adjusts the die wheel 1 so as to turn the particular die number into operative position which corresponds to the thickness of the leather piece determined by the thickness-measuring mechanism. As the leather piece proceeds, its forward end passes between the regulating rolls of the evening mechanism while the stock is still held between the receiving rolls, and as soon as the stock lifts the upper regulating roll, the setting mechanism is thereby locked against movement in any direction by the engagement of the bolts 59 with the cams 35. The positively driven rolls of the evening mechanism compel the stock to move forward into engagement with the skiving knife, thereby rendering the forward end of said stock absolutely even, and as this forward end reaches the rolls 6, 7, it forcibly lifts the upper roll and thereby, through the links 10 and connected parts, actuates the striker 14 (which constitutes the impression device in the wording of certain claims) to deliver a blow against the under side of the leather immediately beneath the selected die 2 of the die wheel 1. As the leather at the point where it is thus marked has been skived to an absolutely even thickness, the result is that the mark which is made is clear and accurate, so that the sole or other leather piece cannot be mistaken thereafter for a different iron or grade from that which it actually is. Also, as the forward movement of the leather itself trips the striker of the marking mechanism, it follows that the marking of all the pieces graded takes place at an absolutely uniform distance from the front end of the stock. Moreover, as the die is stationary at the moment when the stock is marked by it, the marking is rendered clean-cut or clear without blurring,—a feature of considerable practical advantage, as distinguished from having the marker turn or swing or otherwise move down upon the stock at the moment of marking. As the stock, at the moment of marking, is under continuous forward movement, it is of advantage to have the marking accomplished by an instantaneously operated striker. For this reason the striker is relatively heavy and the operating mechanism therefor is given a sudden strong upward impulse which tends to throw the striker with a hammerlike impact against the leather, whereupon the striker drops back slightly from the leather. By having

125

130

the leather held against slipping at its opposite ends and positively pulled forward by the rolls 6, 7 against the retarding action or pull of the skiving knife, the leather is maintained flat and under more or less strain, which, in connection with the upward bending of the stock under the blow of the striker, still further tends to produce a neat, clear accurate marking on the leather 10 at the spot desired.

It will be understood that my invention is capable of a wide variety of mechanical embodiments within the spirit and scope of the broader of my claims as hereinafter set 15 forth.

Having described my invention, what I claim as new and desire to secure by Letters Patent is:

1. In a machine for grading leather shoe-20 parts, a movable marker having a tendency to oscillate, means for automatically adjusting said marker to the grade of the leather piece, means to hold said marker stationary at the moment of marking, and means for 25 forcibly pressing the leather against the marker while thus held stationary.

2. In a machine of the class described, means for positively holding a leather piece at its opposite ends, a marker for marking 30 the leather piece between said ends, and means coöperating with the holding means for one of the ends for exerting pressure between the leather piece and marker, combined with means for automatically adjusting 35 said marker to the grade of the leather piece.

3. In a machine of the class described, means for engaging the opposite sides of a leather piece whose thinnest portion is to be 40 ascertained, coöperating mechanism for co-operating with said engaging means for automatically obtaining the thickness-measurement of said thinnest portion of the leather piece, means for marking said piece 45 in accordance with said measurement, including a marker normally movable but which is stationary at the moment of marking, for engaging the leather piece on one side, means for adjusting said marker to 50 designate the said thickness-measurement, and a pressure-applying device for positively engaging the leather piece on the side opposite to said marker and pressing said piece against the marker.

55 4. In a machine of the class described, the combination with means controlled by the leather pieces for regulating the thickness-mark with which said pieces are to be marked, and normally movable means for 60 marking in accordance therewith a series of leather pieces at the same unvarying distance from one end, including means for maintaining said marker stationary at the moment of marking.

65 5. In a machine of the class described,

marking mechanism, including a marker which is stationary at the moment of marking, and coöperating mechanism automatically actuated to effect the marking at a pre-determined distance from one end thereof, 70 combined with means for obtaining the grade of the leather piece, and means for adjusting said marking mechanism to mark the leather piece in accordance with the grade thus obtained. 75

6. In a machine of the class described, a marker which is stationary at the moment of marking, and coöperating mechanism automatically actuated by the presence of the leather piece to press said marker and 80 leather piece together, combined with means for automatically obtaining the grade of the leather piece at the thinnest point thereof, and means for automatically adjusting said marker to the grade thus obtained. 85

7. In a machine of the class described, means for automatically obtaining the grade of a leather piece, an adjustable marker for marking the leather piece in accordance with said grade, means for automatically 90 adjusting said marker to the grade thus obtained, a striker located to engage the leather piece opposite said marker and strike the leather against the marker to receive the grade-mark, and tripping mechanism actuated by the leather piece for so operating said striker. 95

8. In a machine of the class described, means for automatically obtaining the grade of a leather piece, an adjustable marker for marking the leather piece in accordance with said grade, means for automatically adjusting said marker to the grade thus obtained, said marker being stationary at the moment of marking, a striker located to engage the leather piece opposite said marker and strike the leather against the marker when the latter is stationary, and tripping mechanism actuated by the leather piece for so operating said striker. 100 105 110

9. In a machine of the class described, a marker for engaging the upper side of a leather piece, a striker for momentarily engaging the under side of said leather piece, and tripping means actuated by the leather piece for throwing said striker with a hammerlike blow upward against the leather piece combined with means for automatically obtaining the grade of the leather piece, and means for adjusting said marker to the grade thus obtained. 115

10. In a machine of the class described, a marker for engaging the upper side of a leather piece, a striker for momentarily engaging the under side of said leather piece, and tripping mechanism actuated by the leather piece for throwing said striker with a hammerlike blow upward against the leather piece, constructed to permit the striker to drop back instantly, combined with 125 130

- means for automatically obtaining the grade of the leather piece, and means for adjusting the said marker to the grade thus obtained.
5. 11. In a machine of the class described, a marker, automatic thickness-measuring mechanism for feeling of a leather piece and detecting the thinnest portion thereof, setting mechanism automatically controlled by 10 said first named mechanism for setting said marker in accordance with the thickness detected at said thinnest portion, locking means for locking and holding stationary the marker against movement in any direction when set, and means coöperating with said marker for marking the leather piece when in position to be marked.
12. In a machine of the class described, a marker, automatic thickness-measuring 20 mechanism for feeling of a leather piece, setting mechanism for setting said marker in accordance with the thickness measured, automatic means actuated by the presence of the leather piece for locking the marker 25 when set, and means coöperating with said marker for marking the leather piece when in position to be marked.
13. In a machine of the class described, work-receiving members, setting mechanism 30 and connections therefrom responsive to said members, locking means operated by the work for locking said setting mechanism, and marking mechanism including a marker adjusted by said setting mechanism 35 for marking the work while the work is still locking said setting mechanism.
14. In a machine of the class described, means, including a marking die, controlled by the thinnest portion of the material, for 40 regulating the thickness to which the material is to be marked, an impression device coöperating with the die, means adapted to engage said device for forcing the material by means of said impression device against 45 the marking die, and means controlled by the presence of the material for causing the last said means to operate the impression device, the impression-device operating- means being constructed and arranged to 50 return to its normal position when the said impression device assumes its normal position.
15. In a machine of the class described, the combination of means including a marking die controlled by the thinnest portion of 55 the material for regulating the thickness to which the material is to be marked, said first mentioned means also including means controlled by the presence of the material 60 for automatically setting said die, an impression device coöperating with the die, means adapted to engage said device for forcing the material against the marking die, means controlled by the presence of the 65 material for causing the last said means to operate the impression device, said impression-device operating-means being constructed and arranged to return to its normal position when the said impression device assumes its normal position, and means 70 for automatically returning said die and the regulating means to their normal positions when the material is no longer present.
16. In combination, in a machine of the class described, a marking device, comprising a marking die, and an impression device, between which die and impression device the material is adapted to pass, means controlled by the presence of the material for automatically setting said die, a member 75 adapted to be moved into engagement with the impression device for causing the latter to force the material against the die, a movable member adapted to be engaged by the material, and a connection between said members for operating the first one of said members.
17. In combination, in a machine of the class described, a marking device comprising a die and an impression device, between 80 which die and impression device the material is adapted to pass, means controlled by the presence of the material for automatically setting the die, an inclined support, a member one end of which rests upon 85 the support, the other end being adapted to be brought into engagement with the impression device for causing the latter to force the material against the die, a movable member adapted to be engaged by the material, and a connection between said members for operating the first one of said members.
18. In combination, in a machine of the class described, a marking device comprising a die and an impression device, between 90 which die and impression device the material is adapted to pass, means controlled by the presence of the material for automatically setting the die, an inclined support, a member one end of which rests upon 95 the support, the other end being adapted to be brought into engagement with the impression device for causing the latter to force the material against the die, a movable member adapted to be engaged by the material, and a connection between said members for operating the first one of said members.
19. In a machine of the class described, means for marking a leather piece, including an automatically adjustable marker which is stationary at the moment of marking, for engaging the leather piece on one 100 side, and a pressure-applying device for positively engaging the leather piece on the opposite side and pressing the same against the marker, combined with means for obtaining the grade of the leather piece, means 105

for adjusting said marker to said grade of
the leather piece prior to said marking and
pressure-applying operations, and power op-
erating mechanism for automatically actu-
ating the aforesaid mentioned parts of the
machine in the aforesaid timed relation to
each other.

In testimony whereof, I have signed my
name to this specification, in the presence of
two subscribing witnesses.

PAUL J. LAPHAM.
